(57) **CLAIM**

We claim, the ornamental design for an injection molding machine, as shown and described.

DESCRIPTION

FIG. 1 is a front view of an injection molding machine, showing our new design;

FIG. 2 is an enlarged partial front view thereof;

FIG. 3 is an enlarged partial perspective view thereof;

FIG. 4 is another enlarged partial perspective view thereof;

FIG. 5 is an enlarged partial top view thereof;

FIG. 6 is an enlarged partial front view thereof in an alternate position;

FIG. 7 is an enlarged partial perspective view thereof;

FIG. 8 is another enlarged partial perspective view thereof; and,

FIG. 9 is an enlarged partial top view thereof.

Broken lines in the drawings are used to show portions of the injection molding machine that form no part of the claimed design.

1 Claim, 9 Drawing Sheets
